FIG. 4.

UNITED STATES PATENT OFFICE.

WILLIAM H. RUEPING, OF FOND DU LAC, WISCONSIN, ASSIGNOR TO FRED RUEPING LEATHER COMPANY, OF FOND DU LAC, WISCONSIN, A CORPORATION OF WISCONSIN.

HAIR-WRINGING MACHINE.

1,250,666.

Specification of Letters Patent. Patented Dec. 18, 1917.

Application filed November 29, 1916. Serial No. 134,059.

To all whom it may concern:

Be it known that I, WILLIAM H. RUEPING, a citizen of the United States, residing at Fond du Lac, in the county of Fond du Lac 5 and State of Wisconsin, have invented certain new and useful Improvements in Hair-Wringing Machines, of which the following is a specification.

The object of this invention is to provide 10 an improved machine for wringing water from wet hair, wool and other similar materials preparatory to placing such materials in a drying apparatus.

In the accompanying drawings, Figure 1 15 is a vertical longitudinal central sectional view of a machine embodying the features of my invention. Fig. 2 is a fragmental side elevation of the machine. Fig. 3 is a rear end elevation. Fig. 4 is a sectional view 20 taken in the plane of dotted line 4—4 of Fig. 1.

The embodiment herein shown of this invention comprises an endless apron or conveyer 1 arranged in an inclined position. 25 While the conveyer may be of any suitable construction, it preferably comprises two endless chains 2, the links of which are connected by metal slats 3. The chains 2 are supported by the driving sprocket wheels 4 and the idler sprocket wheels 5. Between the wheels 4 and 5 the chains are kept from sagging by means of rails 6 and idlers 7. The idler sprocket wheels 5 are mounted upon a shaft 8, which shaft is journaled in 30 bearing boxes 9 that are adjustable by means of screws 10 to take up slack in the conveyer. The sprocket wheels 4 are fixed upon a shaft 11 which may be driven in any suitable manner. Herein I have shown a 35 spur gear wheel 12 (Fig. 2) fixed upon the shaft 11 and meshing with a pinion 13. The pinion 13 is secured upon a shaft 14. On the shaft 14 is a spur gear wheel 15 that meshes with a pinion 16 (Fig. 1) on the drive shaft 40 17. 18 is the drive pulley.

As hereinbefore stated, the conveyer is arranged in an inclined position. Hair, wool or the like may be placed upon the lower portion of the conveyer between the side 45 guards 1^a, by any suitable means, and will be carried upwardly by the conveyer to the wringing means. While the wringing means may be of any suitable character, that herein illustrated comprises two sets of pressure rolls. Both sets are or may be identi-

cal in construction. In the present embodiment of the invention, each set consists of a rigid roll 19 supported below the upper run of the conveyer and a yieldable roll 20 located above the conveyer. The roll 19, 60 which may be of metal, is herein shown as mounted upon a shaft 21. The upper roll 20 is preferably provided with a rubber cover 22. The roll 20 is fixed upon a shaft 23 which is journaled in bearing boxes 24 that 65 are slidable toward and away from the roll 19. The bearing boxes 24 are mounted in guideways 25, and are yieldingly pressed toward the roll 19 by means comprising a yoke 26, rods 27 and compression springs 70 28. The rolls 19 and 20 bear against opposite sides of the slats 3 and squeeze water from the hair or other materials carried by the slats. The water escapes through the spaces between the slats. Any suitable arrangement may be provided to allow the 75 water to drain away from the machine.

After passing between each set of rolls 19 and 20, the layer of hair on the conveyer is broken up and transformed into a fluffy 80 mass by means of beaters 29, one beater being located behind each roll 20. The beaters also serve to strip from the rolls 20 any hair that may cling to said rolls. While the beaters may be of any preferred construction, that herein illustrated comprises a plurality of blades rigidly secured together, the blades being of the same length as the rolls 20. The beaters are rotatably supported so that the blades rotate close to the rolls 20. The 85 beaters 29 may be driven in any suitable manner. Herein I have shown a gear wheel 30 (Fig. 2) fixed upon the drive shaft 17 and meshing with a pinion 31. Rigid with the pinion is a sprocket wheel 32 that carries a sprocket chain 33 which runs over a sprocket wheel 34 fixed to one of the journals of one of the beaters 29. A chain 35 (Figs. 1 and 3) communicates power from 90 said beater to the other beater. 36 is a belt- 95 tightening idler.

Each beater 29 is supported in bearing boxes 37 which are adjustable by means of screws 38, thus providing means for properly locating the beaters with relation to 100 the rolls 20.

The rolls 20 and beaters 29 are covered by a housing 39 which is continued rearwardly over the conveyer and leads to a discharge hopper or spout 40. The housing 39 110

is omitted in Figs. 2 and 3 for the sake of clearness.

A beater 41, which may, if desired, be similar to the beaters 29, is located at the 5 discharge end of the conveyer and serves to remove the hair from the conveyer and force the hair into the spout 40. The beater 41 also is mounted in adjustable bearing boxes 42 so that it may be properly positioned 10 with reference to the conveyer.

A fan 43 is located in a chamber or casing 44 beneath the rear end of the conveyer. The casing 44 communicates at 45 with the 15 lower end or outlet of the discharge spout 40. The air blast issuing from the casing 44 carries the hair to the desired point, as, for example, to a drying machine (not shown).

The fan shaft is provided with a pulley 20 46 (Fig. 3) by means of which the fan is driven from a suitable source of power.

The beater 41 is driven from the beater 29 through a chain 47.

In operation, the water that is squeezed 25 from the hair by the first roll 20 escapes through the openings between the slats and therefore does not wash the approaching hair away from said roll. After passing through the first set of pressure rolls, the 30 position of the hair on the conveyer is changed by the first beater, thus enabling the second set of pressure rolls to express water more effectively than if the position of the hair was not changed. The second 35 and third beaters transform the pressed hair into a fluffy, quick-drying mass.

The fan being located outside the path of the hair, the latter does not impair or interfere with the operation of the fan.

Copies of this patent may be obtained for five cents each, by addressing the "Commissioner of Patents, Washington, D. C."

For the sake of brevity, the term "hair" 40 will be used in the following claims to denote hair, wool and similar material.

I claim as my invention:

1. A hair-wringing machine having, in combination, an endless conveyer for hair, 45 a rotary beater for removing hair from the discharge end of the conveyer, a spout into the upper end of which the hair is discharged by the beater, and a fan for discharging an air blast into the lower portion 50 of the discharge spout for blowing the hair from said spout, said fan being located beneath the discharge end of the conveyer and outside the path of the hair.

2. A hair-wringing machine having, in 55 combination, an endless conveyer for hair, two sets of pressing rolls arranged successively to wring hair advanced by the conveyer, and a rotary beater located between said sets of rolls for changing the position 60 of the hair on the conveyer and for stripping hair from one roll of the set that operates first.

3. A hair-wringing machine having, in 65 combination, an endless conveyer for hair, two sets of wringing devices arranged successively to wring hair advanced by the conveyer, and a device located between said sets of wringing devices for changing the position 70 of the hair on the conveyer, said position-changing device operating in close proximity to the set of wringing devices that operates first, and serving to strip hair from said set of wringing devices.

In testimony whereof, I have hereunto set 75 my hand.

WILLIAM H. RUEPING.
